STEAM GENERATING AND SUPERHEATING APPARATUS

Max H. Kuhner, Worcester, Mass., assignor to
 Riley Stoker Corporation, Worcester, Mass., a
 corporation of Massachusetts

Application October 4, 1937, Serial No. 167,194

4 Claims. (Cl. 122—478)

This invention relates to steam generating and superheating apparatus, and more particularly to the construction and arrangement of a water tube steam boiler having a superheater and a re heater associated therewith.

It has been proposed heretofore to produce power by the expansion of superheated steam, and then to reheat the steam so that additional power may be produced by further expansion thereof without undue condensation. For the most efficient operation it is important to obtain high steam temperatures at the outlet of both the superheater and the re heater, and to control these temperatures accurately. Considerable difficulty has been encountered in obtaining the required accuracy in the control of the steam temperatures, particularly when both the superheater and the re heater are mounted in the same setting with the boiler.

It is accordingly one object of the invention to provide a comparatively simple and inexpensive apparatus for producing superheated steam and reheating the same, which is so arranged that the steam temperatures can be accurately controlled.

It is a further object of the invention to provide a compact and efficient apparatus including a water tube steam boiler, a superheater and a re heater, all mounted in a single setting, together with means for controlling the steam temperatures at the outlets of the superheater and the re heater independently.

With these and other objects in view, as will be apparent to those skilled in the art, the invention resides in the combination of parts set forth in the specification and covered by the claims appended hereto.

In accordance with my invention I provide a boiler and two steam heaters, preferably mounted in a common setting so constructed and arranged as to direct the hot gases from a combustion chamber into contact with the boiler and then into contact with the heaters successively. One of the heaters may be utilized to superheat the steam immediately following its generation, and the other may be utilized to reheat the steam after it has been reduced in temperature and pressure by expansion in a prime mover, such as a turbine. Associated with each heater is a by-pass opening through which a portion of the hot gases can flow, thereby reducing the effectiveness of the heater. Means is provided to control the flow through the two openings independently, so that the temperature of the steam leaving each heater can be regulated as desired without affecting the operation of the other heater.

Referring to the drawing illustrating one embodiment of the invention, and in which like reference numerals indicate like parts, the single figure is a longitudinal vertical section through a water tube boiler and the steam heaters associated therewith.

The embodiment illustrated comprises a rear transverse steam-and-water drum 10 and a rear transverse water drum 11 therebeneath. These drums are connected by a bank of upright water tubes 12, which may be spaced apart rather widely in each row since they are intended to serve primarily as downcomers rather than as steam generators. A transverse header or small water drum 14 is mounted in front of the water drum 11 and 15 at a somewhat higher elevation. Three rows of water tubes 15 extend upwardly and forwardly from the drum 11 to the drum 14, and two rows of water tubes 16 extend upwardly from the drum 14 and then at a slight upward slope rearwardly 20 to the steam-and-water drum 10. These various parts are mounted in a setting shaped to provide a combustion chamber 18 beneath the tubes 15, this setting comprising a rear wall 19, a front wall 20 and side walls 21. The rear wall 19 is 25 protected by means of water tubes 23 connected at their upper ends to the drum 11, and the front wall 20 is protected by means of water tubes 24 connected at their upper ends to the drum 14. The side walls 21 may also be protected by water 30 tubes if desired, but inasmuch as such constructions are well-known, and since an illustration thereof would greatly complicate the drawing and prevent a clear disclosure of the essential features of the invention, such water tubes have not been 35 shown. It will be noted that the tubes 16 serve to support the roof 25 of the boiler setting. At the rear of the setting there is provided a gas outlet duct 26 which in the particular embodiment illustrated is located near the steam-and-water 40 drum 10.

Suitable baffles are provided to direct hot gases in a desired path from the combustion chamber 18 to the gas outlet duct 26. In the preferred construction a main baffle 28 extends forwardly 45 from the water drum 11 and above the tubes 15 for a portion of the lengths of these tubes and then substantially vertically upward, terminating an appreciable distance below the roof 25. This baffle is supported and cooled by a row of water 50 tubes 29 connected at their ends to the drums 10 and 11. A rear baffle 30 extends downwardly from the drum 10 and at the front of the down-comer tubes 12, terminating an appreciable distance 55 above the lower drum 11 to provide an opening

for the rearward flow of the gases. This baffle is supported and cooled by two rows of upright water tubes 31 connected at their ends to the drums 10 and 11. With this construction hot gases from the combustion chamber 18 will flow upwardly in front of the baffle 28, rearwardly over the top thereof, thence downwardly in front of the baffle 30, rearwardly beneath the bottom thereof, and thence upwardly in the rear of the baffle 10 30 to the outlet duct 26.

The hot gases traveling through the setting are utilized not only to generate steam in the water tubes, but also to superheat this steam and to reheat the same. For this purpose there is provided a superheater comprising a group of sinuous tubes 33 located in front of the baffle 28 and connected at their ends to an inlet header 34 and an outlet header 35 mounted above the roof 25. The tubes 33 are supported intermediate their lengths by means of vertical rods 36 suspended from a beam 37. The inlet header 34 is supplied with steam from the steam-and-water drum 18 through a row of tubes 39. Steam from the outlet header 35 flows into a second group of superheater tubes 40 located adjacent the water tubes 15 and connected to an outlet header 41 mounted in front of the boiler setting. From the header 41 the steam may be delivered to any suitable apparatus, such as a steam turbine (not shown). In order to reheat the steam after it has been reduced in temperature in the turbine there is provided a reheater comprising a group of sinuous tubes 43 located between the baffles 28 and 30 and connected at their ends to an inlet header 44 and an outlet header 45 mounted above the roof 25. The tubes 43 are supported intermediate their lengths by means of vertical rods 46 suspended from a beam 47. It will be understood that suitable pipes (not shown) will be provided to deliver steam to the inlet header 44 and to withdraw the reheated steam from the outlet header 45.

Means is provided whereby the temperature of the steam leaving the superheater outlet header 41 and the temperature of the steam leaving the reheater outlet header 45 may be independently controlled. For this purpose both the superheater and the reheater are constructed with slightly greater heating surface than necessary to ensure sufficient heating of the steam, and associated with each of these heaters is a bypass opening or passage through which a portion of the hot gases can flow in such a way as to reduce the effectiveness of the heater. The gas flow in each passage may be controlled independently, thus allowing the desired regulation of the steam temperature. In the preferred construction illustrated an upright baffle 49 is mounted between the superheater tubes 33 and the baffle 28, these baffles being spaced apart to provide a vertical passage 50. The baffle 49 is supported and cooled by means of a row of water tubes 51 connected at their ends to the drums 10 and 11. A damper 53 serves to regulate the gas flow in the passage 50, this damper being controlled by means of a shaft 54 extending outside the setting. The rear baffle 30 is provided with an opening or passage 56 near the steam-and-water drum 10 through which the hot gases may escape to the gas outlet 26 and avoid contact with a large part of the surface area of the reheater tubes 43. The flow through the opening 56 is regulated by means of a damper 57 which is controlled by means of a shaft 58 extending outside the setting. It will be noted that

the reheater 43 extends below the opening 56 for such a distance that by adjusting the damper 57 the heat transfer to the reheater may be varied as desired.

The operation of the invention will now be apparent from the above disclosure. Any suitable fuel is burned in the combustion chamber 18, and the hot gaseous products of combustion travel upwardly therefrom across the water tubes 15 and the superheater tubes 40. Steam is generated in the tubes 15 and in the water wall tubes 23 and 24, and this steam flows through the tubes 16 to the drum 10, thence through the tubes 39 and the superheater tubes 33 and 40 to the header 41. From this header the steam is withdrawn for use in a turbine or other prime mover and then returned to the tubes 43 for reheating. Just above the water tubes 15 the hot gases divide into two streams, a small portion of the gases entering the passage 50 and the remainder flowing in front of the baffle 51 and in contact with the superheater tubes 33. This main gas stream flows rearwardly over the top of the baffle 51, where it mingles with the small stream issuing from the passage 50 under control of the damper 53. Thereupon most of the gases flow downwardly in contact with the reheater tubes 43, beneath the lower edge of the baffle 30, and thence upwardly in the rear of this baffle to the gas outlet 26. A small stream of hot gases however flows rearwardly through the opening 56 under control of the damper 57, these gases contacting with only a small portion of the reheater surface. If the temperature of the steam leaving the superheater header is too high, the damper 53 may be moved toward open position to reduce the gas flow over the tubes 33, and if the steam temperature is too low the damper 53 may be moved toward closed position to increase the gas flow over the tubes 33. These adjustments will not change the gas flow over the reheater 43 nor will they have any appreciable effect on the temperature of the steam leaving the reheater. If the temperature of the reheated stream is too high, the damper 57 may be moved toward open position to reduce the gas flow over the lower portions of the tubes 43, and if the steam temperature is too low the damper 57 may be moved toward closed position to increase the gas flow over the lower portions of the tubes 43. These adjustments will not affect the gas flow over the superheater tubes or the temperature of the superheated steam.

It will now be apparent that the invention provides a comparatively simple and inexpensive construction, including a steam generator, a superheater and a reheater, all mounted in a single setting to form a very compact unit. The construction also includes a simple means whereby the temperature of the superheated steam and the temperature of the reheated steam may be controlled independently. The various baffles which direct the flow of the gases are well supported and cooled by water tubes. Moreover the upright arrangement of the baffles ensures a gravity discharge of any soot which may be deposited on them by the gases.

Having thus described my invention, what I claim as new and desire to secure by Letters Patent is:

1. Steam generating and superheating apparatus comprising an upper transverse steam-and-water drum, a lower transverse water drum, a substantially upright transverse baffle located between the drums and having an upper opening 75

- and a lower opening therethrough, a damper to control the upper opening, downcomers connecting the drums, water tubes extending upwardly and forwardly from the water drum, means connecting the front ends of the water tubes to the steam-and-water drum, a steam heater mounted above the front portions of the water tubes, a second steam heater mounted above the rear portions of the water tubes and in front of said transverse baffle, means providing a combustion chamber beneath the water tubes, a main baffle extending forwardly from the water drum beneath the second heater and then upwardly between the heaters, the hot gases flowing upwardly from the combustion chamber in contact with the first heater and thence rearwardly and downwardly in contact with the second heater, means providing a by-pass for hot gases adjacent the first heater, and a damper to control the by-pass, the second heater extending below the said upper opening for such a distance that by adjusting the first-mentioned damper the heat transfer to the second heater may be varied.
2. Steam generating and superheating apparatus comprising an upper transverse steam-and-water drum, a lower transverse water drum, a substantially upright transverse baffle located between the drums and having an upper opening and a lower opening therethrough, a damper to control the upper opening, downcomers connecting the drums, water tubes extending upwardly and forwardly from the water drum, means connecting the front ends of the water tubes to the steam-and-water drum, a steam heater mounted above the front portions of the water tubes, a second steam heater mounted above the rear portions of the water tubes and in front of said transverse baffle, means providing a combustion chamber beneath the water tubes, a main baffle extending forwardly from the water drum beneath the second heater and then upwardly between the heaters, the hot gases flowing upwardly from the combustion chamber in contact with the first heater and thence rearwardly and downwardly in contact with the second heater, the first heater being spaced forwardly from the main baffle to provide a by-pass for hot gases, and a damper to control the by-pass, the second heater extending below the said upper opening for such a distance that by adjusting the first-mentioned damper the heat transfer to the second heater may be varied.
3. Steam generating and superheating apparatus comprising a rear transverse steam-and-water drum, a transverse rear water drum therebeneath, a rear baffle extending downwardly from the steam-and-water drum and terminating above the water drum, an opening in the upper portion of the baffle, a damper to control the opening, downcomers connecting said drums in the rear of the baffle, water tubes extending upwardly and forwardly from the rear water drum to the front water drum, a steam heater mounted above the front portions of the water tubes, a second steam heater mounted above the rear portions of the water tubes and in front of said rear baffle, water tubes extending upwardly from the front water drum and then rearwardly above the steam heaters to the steam-and-water drum, means providing a combustion chamber beneath the first-mentioned water tubes, a main baffle extending forwardly from the rear water drum beneath the rear heater and then upwardly between the heaters, an upright baffle between the front heater and the main baffle and spaced from the main baffle to provide a passage through which a portion of the hot gases may flow upwardly from the combustion chamber, the remainder of the hot gases flowing upwardly in contact with the front heater, and a damper to control the flow in the passage, the second heater extending below said opening for such a distance that by adjusting the first-mentioned damper the heat transfer to the second heater may be varied.

MAX H. KUHNER.
